US0D1073279S

(12) **United States Design Patent** (10) **Patent No.:** **US D1,073,279 S**
(45) **Date of Patent:** **** May 6, 2025**

(54) **FOOTWEAR SOLE**

(71) Applicant: **Crocs, Inc.**, Broomfield, CO (US)

(72) Inventors: **Brian Douglas Rottman**, Englewood, CO (US); **Jie Liu**, Pasadena, CA (US); **Michael Sarantakos**, Portland, OR (US)

(73) Assignee: **Crocs, Inc.**, Broomfield, CO (US)

(***) Term: **15 Years**

(21) Appl. No.: **29/920,666**

(22) Filed: **Dec. 12, 2023**

(51) LOC (15) Cl. **02-04**

(52) U.S. Cl.

USPC **D2/947; D2/953**

(58) **Field of Classification Search**

(57) **CLAIM**

The ornamental design for footwear sole as shown and described.

DESCRIPTION

FIG. 1 is a top perspective view of footwear sole;

FIG. 2 is a front view thereof;

FIG. 3 is a back view thereof;

FIG. 4 is an inner side view thereof;

FIG. 5 is an outer side view thereof;

FIG. 6 is a top view thereof; and,

FIG. 7 is a bottom view thereof.

The elements shown in FIGS. 1-7 that are overlaid with a white transparent mask bounded by broken lines represent portions that form no part of the claimed design.

1 Claim, 2 Drawing Sheets
